(57) **CLAIM**

What is claimed is; the ornamental design for, an air cleaner cover for a motorcycle, as shown and described

DESCRIPTION

FIG. 1 is a front perspective view of an air cleaner cover for a motorcycle, showing our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The portions shown in broken lines form no part of the claimed design.
